UNITED STATES PATENT OFFICE.

JULIUS LEHMANN, OF NEW YORK, N. Y., ASSIGNOR TO THE HANNOVER GUMMI-KAMM COMPANY, ACTIEN GESELLSCHAFT, OF HANOVER, GERMANY.

DESIGN FOR A COMB.

SPECIFICATION forming part of Design No. 27,284, dated July 6, 1897.

Application filed May 19, 1897. Serial No. 637,295. Term of patent 3½ years.

To all whom it may concern:

Be it known that I, JULIUS LEHMANN, a citizen of the United States, residing in the city, county, and State of New York, have invented and produced a new and original Design for a Comb, of which the following is a specification.

The leading feature of my design is a comb having its back ornamented with substantially parallel sinuous ridges with intervening depressions, imparting to said comb-back the configuration or appearance of a stick of bamboo.

The accompanying drawing shows a comb embodying my design.

In the drawing, *a* indicates the comb-back, which is ornamented with substantially parallel sinuous ridges *b*, between which are depressions *c*, imparting to the said back the appearance of bamboo. Teeth *d* project from the comb-back.

What I claim is—

The design for a comb, substantially as shown.

JULIUS LEHMANN.
